Application June 24, 1949, Serial No. 101,200

4 Claims. (Cl. 200—33)

1

My invention relates to electric heating switch, and the principal object of my invention is to provide improved means for controlling the energization of one or more electric heaters.

One application for which my invention is particularly suitable is to control one or more top units of an electric range or hot plate, for example, all four of the top units of a customary four-top-unit electric range, and I have herein illustrated my invention in this utilization.

Therefore in the drawings accompanying this specification and forming a part of this application I have shown for purposes of illustration what I now consider to be the best modes of carrying my invention into practice in this particular utilization, and in these drawings:

Figures 1 through 4 are diagrammatic representations of four circuit arrangements for that purpose;

Figure 5 is an elevation of one form of switch mechanism suitable for either the arrangement of Figure 1 or the arrangement of Figure 3;

Figure 6 is an elevation of one form of switch mechanism suitable for either the arrangement of Figure 2 or the arrangement of Figure 4;

Figure 7 is a general view of the switch means of either the mechanism of Figure 5 or the mechanism of Figure 6;

Figures 8 and 9 are views indicating other positions of the switch means of Figure 7;

Figure 10 is an elevation of a second form of switch mechanism suitable for either the arrangement of Figure 1 or the arrangement of Figure 3;

Figure 11 is an elevation of a second form of switch mechanism suitable for either the arrangement of Figure 2 or the arrangement of Figure 4;

Figure 12 is a general view of the switch means of either the mechanism of Figure 10 or the mechanism of Figure 11;

Figures 13 and 14 are views indicating other positions of the switch means of Figure 12;

Figure 15 is a view showing a supplemental cam desirable in the utilization of either of the above switch means in either the arrangement of Figure 1 or the arrangement of Figure 3; and

Figures 16 through 18 are views indicating three positions of the above supplemental cam and of the supplemental switch means controlled thereby.

In Figures 1 and 2 I have illustrated two methods of utilization in conjunction with four top units 21 each comprising two heating ele-

2

ments or races 22 and 23 each designed to be energized at the same voltage, and according to either of these arrangements the two races of each unit are operatively connected in parallel, as indicated by the conductors 24 and 25.

In the arrangement represented in Figure 1, current is supplied by two supply conductors 26 and 27 to which is connected a synchronous electric clock 28, and each of the units 21 is connected to the supply conductors 26 and 27 respectively by a branch conductor 29 in which is interposed a control switch 30 and a branch conductor 31 in which may be interposed a supplemental switch 32.

In the arrangement represented in Figure 2, current is supplied from a three-wire feed consisting of potential conductors 33 and 34 and a neutral conductor 35, through a three-pole ready switch 36, to potential conductors 37 and 38 and a neutral conductor 39, and connected to the potential conductor 37 and the neutral conductor 39 is a synchronous motor 40, connected to the potential conductor 38 and the neutral conductor 39 is a tell-tale lamp 41, each of the units 21 is connected to the potential conductors 37 and 38 by branch conductors 42 and 43, and in each branch conductor 42 is interposed a control switch 44.

With the foregoing, if a switch 32 of a unit 21 of Figure 1 is in closed position and the switch 30 of that unit is closed, or if the switch 44 of a unit 21 of Figure 2 is closed, the two elements 22 and 23 of that unit will each be connected to rated voltage, and the unit will be fully energized, and will deliver full rated heat, whereas if the switch 30 or 44 is open, both races of the respective unit will be disconnected, not energized, and will deliver no heat.

On the other hand, if the switch 32 of a unit 21 of Figure 1 is in closed position and the switch 30 of that unit is cycled between open and closed positions by means of the clock 28, or if the switch 44 of a unit 21 of Figure 2 is cycled between open and closed positions by means of the motor 40, thereupon that unit will be energized and will deliver that proportion of its rated heat dependent upon and directly proportional to the proportion of each cycle during which the switch 30 or 44 is in closed position.

Optionally the arrangement of Figure 1 may include a neutral conductor, and in that event the clock 28 may be connected to this neutral conductor and one of the conductors 26 and 27, in any event the arrangement of Figure 1 may include a tell-tale lamp similar to the lamp 41

of Figure 2 and connected either to the two conductors 26 and 27 or to one of these and the indicated neutral conductor, and on the other hand, in the arrangement of Figure 2 the ready switch 36 may be only two-pole, omitting the neutral, and either the neutral conductor 39 may be connected directly to the neutral conductor 35 or the neutral conductors 35 and 39 may be omitted entirely and the motor 40 and lamp 41 connected to the two potential conductors 37 and 38, also the lamp 41 may be omitted entirely.

In Figures 3 and 4 I have illustrated two methods of utilization in conjunction with four top units 51 each comprising an element or race 52 designed to be energized at a higher voltage and an element or race 53 designed to be energized at a lower voltage, for example, one half of the higher voltage, and according to either of these arrangements the races 52 and 53 of each unit 51 are connected together on one side, as indicated by the conductors 54.

In the arrangement represented in Figure 3, current is supplied by a three-wire feed consisting of potential conductors 55 and 56 and a neutral conductor 57, and a synchronous electric clock 58 is connected to the potential conductors 55 and 56.

The one side of the elements or races 52 and 53 of each of the units 51a and 51d is connected to the potential conductor 55, respectively by branch conductors 59a and 59d, the one side of the elements or races 52 and 53 of each of the units 51b and 51c is connected to the potential conductor 56, respectively by branch conductors 59b and 59c, and interposed in each of the branch conductors 59 is a control switch 60.

The other side of the high voltage element or race 52 of each of the units 51a and 51d is connected to the potential conductor 56, respectively by branch conductors 61a and 61d, the other side of the high voltage element or race 52 of each of the units 51b and 51c is connected to the potential conductor 55, respectively by branch conductors 61b and 61c, the other side of the low voltage element or race 53 of each of the units 51 is connected to the neutral conductor 57, by a branch conductor 62, and optionally interposed in each of the conductors 61 is a supplemental switch 63.

In the arrangement indicated in Figure 4, current is supplied from a three-wire feed consisting of potential conductors 64 and 65 and a neutral conductor 66, through a three-pole ready switch 67, to potential conductors 68 and 69 and a neutral conductor 70, and connected to the potential conductor 68 and the neutral conductor 70 is a synchronous motor 71, and connected to the potential conductor 69 and the neutral conductor 70 is a tell-tale lamp 72.

The one side of the elements or races 52 and 53 of each of the units 51a and 51d is connected to the potential conductor 68, respectively by branch conductors 73a and 73d, the one side of the elements or races 52 and 53 of each of the units 51b and 51c is connected to the potential conductor 69, respectively by branch conductors 73b and 73c, and interposed in each of the branch conductors 73 is a control switch 74.

The other side of the high voltage element or race 52 of each of the units 51a and 51d is connected to the potential conductor 69, respectively by branch conductors 75a and 75d, the other side of the high voltage element or race 52 of each of the units 51b and 51c is connected to the potential conductor 68, respectively by

branch conductors 75b and 75c, and the other side of each of the low voltage elements or races 53 is connected to the neutral conductor 70, by a branch conductor 76.

With the foregoing, if a switch 63 of a unit of Figure 3 is in closed position and the switch 60 of that unit is also closed, or if the switch 74 of a unit of Figure 4 is closed, the two elements or races 52 and 53 of the respective unit will be connected each to its rated voltage, and the unit will be fully energized and will deliver full rated heat, whereas if the switch 60 or 74 is opened, the two elements or races of the respective unit will be connected in series to the rated voltage of the element or race 53 and the unit will be only fractionally energized and will deliver only a fraction of its rated heat, the fraction depending on the relative resistances of the two elements or races 52 and 53.

On the other hand, if the switch 63 of a unit of Figure 3 is in closed position and the switch 60 of that unit is cycled between open and closed positions by means of the clock 58, or if the switch 74 of a unit of Figure 4 is cycled between open and closed positions by means of the motor 71, thereupon that unit will be energized and will deliver that proportion of its rated heat, within the range from the fractional amount of the series connection to full rated capacity, dependent upon and determined directly by the proportion of each cycle during which the switch 60 or 74 is in closed position.

As an example, if the two elements or races are of equal wattage, for which the resistance of the element or race 53 would be one-fourth the resistance of the element or race 52, thereupon the fractional energization in the series relation would be one-tenth, in the series relation the unit would deliver one-tenth its rated heat, and under the cycling operation of the switch 60 or 74 the heat delivered by the unit would be variable from 10% to 100% of the full rated heat of the unit.

In this respect, normally there is no occasion to operate a top unit of an electric range or hot plate below 10%, also normally there is no occasion to operate such a unit below 100% and at more than approximately 60 to 75%.

Optionally the arrangement of Figure 3 may include a tell-tale lamp similar to the lamp 72 of Figure 4 and connected to the two potential conductors 55 and 56 or to one of these and the neutral conductor 57, in the arrangement of Figure 3 the clock 58 may be connected to the neutral conductor 57 and one of the potential conductors 55 and 56, and in the arrangement of Figure 4 the ready switch 67 may be only two pole, omitting the neutral, and the neutral conductor 70 connected directly to the neutral conductor 66, either or both of the motor 71 and lamp 72 may be connected to the two potential conductors 68 and 69, and also the lamp 72 may be omitted entirely.

Further, if any of the units 21 or 51 are of the sheathed type, the two elements or races 22 and 23 or 52 and 53 of each unit may be in separate sheaths, or may be included in a single sheath.

In any of the arrangements of Figures 1 through 4, the control switches 30, 44, 60, or 74, may be provided by the switches 81 of the switch mechanisms 82 and 83 shown in Figures 5 through 9, or by the switches 111 of the switch mechanisms 112 and 113 shown in Figures 10 through 14.

As shown in Figures 5 and 6, each of the switch mechanisms 82 and 83 comprises four control knobs or handles 84, the switch mechanism 82 comprises on its front a clock 85 suitable to constitute the clock 28 or 58 of the arrangements of Figures 1 and 3, and therefore is intended particularly for utilization with the arrangements of Figures 1 and 3, and the switch mechanism 83 comprises on its rear a synchronous motor 86 suitable to constitute the motor 40 or 71 of the arrangements of Figures 2 and 4, and on its front a lamp 87 suitable to constitute the lamp 41 or 72 of the arrangements of Figures 2 and 4, and therefore is intended particularly for utilization with the arrangements of Figures 2 and 4.

As shown in Figure 7, each of the switches 81 comprises an actuated electrically-conducting resilient arm 88 and a cooperating electrically-conducting resilient arm 89, and the arms 88 and 89 are provided at their outer ends with integral lateral extensions 90 by which the arms are riveted or otherwise suitably mounted to a common electrically-insulating base 91, and are provided at their inner ends with cooperating contacts 92 located to be brought into engagement upon suitable actuation of the actuated arms 88, thus to close the respective switch 81.

For this purpose the four switches 81 are disposed about a common cam 93, fixed to and rotatable by a shaft 94 operated either by the clock 85 of the mechanism of Figure 5 or by the motor 86 of the mechanism of Figure 6, and constructed and arranged upon such rotation to cyclically sequentially actuate the actuated arms 88 and bring the contacts 92 into engagement, but under the control of individual switch control means 95.

In the present embodiment, each of the control means 95 comprises a shaft 96, constructed to receive and be operated by the respective control knob or handle 84 and provided with two cams, an actuated-arm control cam 97 located to act upon a coacting follower surface 98 unitary with the respective actuated arm 88 and thereby to determine the primary position of the respective actuated arm 88, and a cooperating-arm control cam 99 located to act upon a coacting follower surface 100 unitary with the respective cooperating arm 89 and thereby to determine the primary position of the respective cooperating arm 89.

As herein shown, each of the actuated-arm control cams 97 comprises a substantially concentric portion 101 subtending what will be referred to as the variable range, and a projecting portion 102 subtending what will be referred to as the "off" and "on" positions, and each of the cooperating-arm control cams 99 comprises an "off" projection 103, a higher "on" projection 104, and a variable range portion 105 rising continually from adjacent the "on" projection 104 to adjacent the "off" projection 103, but the high end of which is substantially below the elevation of the "off" projection 103.

In the position in which the parts are shown in Figure 7, each of the control means 95 is set for cycling operation, and for maximum period of closure of the contacts 92 during each cycle of the actuating cam 93. However, in the present embodiment, as indicated by the positions of the arms 88 and 89 of the switches 81a and 81b, even in this adjustment the cooperating-arm control cams 99 hold the cooperating arms 89 at such elevation that the contacts 92 are open during a substantial portion of each cycle of the actuating

cam 93, as herein shown, approximately 20% of each cycle.

Further, by reason of the contour of the co-operating-arm control cam 99, upon rotation of a control means 95, in the clockwise direction as viewed in Figure 7, the respective operating arm 89 is progressively raised, whereby progressively the contacts 92 are closed only during a correspondingly decreased portion of each cycle, until at the end of the variable range portion 105 the contacts 92 remain open throughout substantially the entirety of each cycle.

Therefore each of the control means 95 is effective to vary the portion of each cycle during which the contacts 92 of the respective switch 81 are closed, to cause the contacts 92 to be closed during any desired proportion of the cycle from a maximum substantially less than 100%, as herein shown, approximately 80%, to and including substantially zero.

Thus in conjunction with the actuating cam 93, each control means 95 is effective over the variable range to cause a respective unit 21 to generate any proportion of full rated heat between a maximum substantially less than 100%, as herein shown, approximately 80%, and a minimum substantially zero, or to cause a respective unit 51 to generate any proportion of full rated heat between a maximum substantially less than 100%, as herein shown, the sum of approximately 80% plus the product of approximately 20% multiplied by the fraction of full heat generated in the series relation, and a minimum substantially that fraction, or under the previous example of that fraction as one-tenth, as herein shown, between a maximum of approximately 82% and a minimum of approximately 10%.

As indicated in Figure 8, upon further rotation of the control means 95, the actuated-arm control cam 97 raises the actuated arm 88 entirely out of the path of the actuating cam 93, but the cooperating-arm control cam 99 raises the cooperating arm 89 still further, resulting in the contacts 92 being maintained separated, and thereby providing a "full off" condition.

As indicated in Figure 9, upon still further rotation of the control means 95, the actuated-arm control cam 97 still holds the actuated arm 88 out of the path of the actuating cam 93, but the cooperating-arm control cam 99 raises the cooperating arm 89 still higher, thereby bringing a further contact 106 carried on the reverse side of the arm 89, into engagement with a stationary contact 107 mounted on an L-shape electrically-conducting post 108 riveted or otherwise suitably mounted to the base 91 and electrically connected to the actuated arm 88 as by a conductor 109, and thereby providing a "full on" position.

Further rotation of a control means 95 from the above "full on" position results in again bringing the parts into the variable range portion previously described. However, in the present embodiment the control means 95 are rotatable in either direction.

As shown in Figures 10 and 11, each of the switch mechanisms 112 and 113 comprises four control knobs or handles 114, the switch mechanism 112 comprises on its front a clock 115 suitable to constitute the clock 28 or 58 of the arrangements of Figures 1 and 3, and therefore is intended primarily for utilization with the arrangements of Figures 1 and 3, and the switch mechanism 113 comprises at one side a motor 116 suitable to constitute the motor 40 or 71 of

the arrangements of Figures 2 and 4, and on its front a lamp 117 suitable to constitute the lamp 41 or 72 of the arrangements of Figures 2 and 4, and therefore is intended particularly for utilization with the arrangements of Figures 2 and 4.

As shown in Figure 12, each of the switches 111 comprises an actuated electrically-conducting resilient arm 118 and a cooperating electrically-conducting resilient arm 119, and the arms 118 and 119 are provided at their outer ends with integral lateral extensions 120 by which the arms are riveted or otherwise suitably mounted to a common electrically-insulating base 121, and are provided at their inner ends with cooperating contacts 122 located to be brought into engagement upon suitable actuation of the actuated arm 118, thus to close the respective switch 111.

For this purpose the four switches 111 are disposed in parallel relation and arranged to be actuated respectively by a series of four cams 123 fixed to and rotatable by a shaft 124 operated either by the clock 115 of the mechanism of Figure 10 or by the motor 116 of the mechanism of Figure 11 and constructed and arranged upon such rotation to cyclically sequentially actuate the actuated arms 118 and bring the contacts 122 into engagement, but under the control of individual switch control means 125.

In the present embodiment, each of the control means 125 comprises a shaft 126 constructed to receive and be operated by the respective control knob or handle 114 and provided with two cams, an actuated-arm control cam 127 located to act upon a coacting follower surface 128 unitary with the respective actuated arm 118 and thereby to determine the primary position of the respective actuated arm 118, and a cooperating-arm control cam 129 located to act upon a coacting follower surface 130 unitary with the respective cooperating arm 119 and thereby to determine the primary position of the respective cooperating arm 119.

As herein shown, each of the actuated-arm control cams 127 comprises a substantially concentric portion 131 subtending what will be referred to as the variable range, and a projecting portion 132 subtending what will be referred to as the "off" and "on" positions, and each of the cooperating-arm control cams 129 comprises an "off" projection 133, and lower "on" projection 134, and a variable range portion 135 rising from adjacent the "on" projection 134 to adjacent the "off" projection 133, but the high end of which is substantially below the elevation of the "on" projection 134.

In the position in which the parts are shown in Figure 12, each of the control means 125 is set for cycling operation, and for maximum period of closure of the contacts 122 during each cycle of the actuating cams 123, and as indicated by the positions of the arms 118 and 119 of the various switches 111, in the present embodiment in this position of the control means 125 the contacts 122 are in engagement during substantially the entirety of each cycle.

However, by reason of the contour of the cooperating-arm control cam 129, upon rotation of a control means 125, in the clockwise direction as viewed in Figure 12, the respective cooperating arm 119 is progressively raised, whereby progressively the contacts 122 are closed only during a corresponding decreased portion of each cycle, until at the end of the variable range portion 135 the contacts 122 remain open throughout substantially the entirety of each cycle.

Therefore each of the control means 125 is effective to vary the portion of each cycle during which the contacts 122 of the respective switch 111 are closed, to cause the contacts 122 to be closed during any desired proportion of the cycle, from a maximum substantially 100% to a minimum substantially zero.

Thus in conjunction with the actuating cams 123, each control means 125 is effective over the variable range to cause a respective unit 21 to generate any proportion of full rated heat between a maximum substantially 100% and a minimum substantially zero, or to cause a respective unit 51 to generate any proportion of full rated heat between a maximum substantially 100%, and a minimum substantially the fraction of full heat generated in the series relation, under the previous assumption, approximately 10%.

As indicated in Figure 13, upon further rotation of the control means 125 the actuated-arm control cam 127 raises the actuated arm 118 entirely out of the path of the respective actuating cam 123, but the cooperating-arm control cam 129 raises the cooperating arm 119 still further, whereby the contacts 122 are maintained separated, thereby providing a "full off" position, and as indicated in Figure 14, upon still further rotation of the control means 125, the actuated-arm control cam 127 still holds the actuated arm 118 out of the path of the respective actuating cam 123, but the cooperating-arm control cam 129 permits the cooperating arm 119 to drop to bring the contacts 122 into engagement, thereby providing a "full on" position.

Further rotation of a control means 125 from the above "full on" position results in again bringing the parts into the variable range previously described. However, in the present embodiment the control means 125 are rotatable in either direction.

With any of the mechanisms of Figures 5 through 14, the period of each cycle desirably should be sufficiently short to avoid objectionable variation in temperature of the heating unit under the cycling operation, and on the other hand, for the purpose of avoiding unnecessary wear and fatigue of the parts, should not be shorter than is necessary, and under these considerations, in the event of sheathed units the duration suitably may be of the order of from 60 to 120 seconds, depending partly upon the thermal lag exhibited by the particular construction of heating unit employed, and in any event being permissibly somewhat longer than the arrangements of Figures 3 and 4, by reason of the energization not being entirely interrupted.

As herein shown, in the switch means of Figures 5 through 9 the switches 81 are substantially equally spaced about the actuating cam 93, and in the switch means of Figures 10 through 14 the actuating cams 123 are substantially equally spaced angularly about the axis of the shaft 124, thus tending to even the power demand when more than one of the units 21 or 51 are concurrently energized under cycling operation.

In either of the switch means herein illustrated, preferably the contour of each actuating cam 93 or 123 is substantially uniformly accelerating over approximately the first half of its periphery and then substantially uniformly decelerating over approximately the second half of its periphery, thus tending to smooth the action of the cams on the respecting actuated arm 88 or 118, except only for the movement at the step of the cam.

On the other hand, the inclusion of the step,

together with the relative location of the parts, provides the desirable feature of quick separation of the contacts 92 or 122, and therefore operates to reduce arcing between the respective contacts on separation of the contacts under load, and thus to increase the life of the contacts.

Further, raising the actuated arms 88 or 118 out of engagement with the actuated cam 93 or cams 123 in both the "full off" and "full on" positions, results in eliminating unnecessary wear of the cam or cams 93 or 123 and of the actuated arms 88 or 118, and unnecessary fatigue of the actuating arms 88 or 118 and of the cooperating arms 89 or 119.

This is particularly important in the arrangements of Figures 1 and 3, in which as herein shown the cam or cams 93 or 123 operate continuously, as distinguished from the situation in the arrangements of Figures 2 and 4, in which properly the ready switch 36 or 67 is closed only preparatory to utilization of any of the units 21 or 51, and is opened upon cessation of utilization of any of the units, whereby the respective motor is connected, and the cam or cams 93 or 123 are in operation, only during periods of actual utilization of one or more of the units 21 or 51.

In the arrangements of Figures 2 and 4, inasmuch as the units 21 or 51 also are connected on the load side of the ready switch 36 or 67, therefore the ready switch 36 or 67 serves also to completely disconnect the units 21 or 51 at least from the potential conductors, and thus to meet a requirement to that effect prevailing in many localities.

For this reason a suitable ready switch may be included also in the arrangements of Figures 1 and 3, or these arrangements may comprise the individual switches 32 and 63 heretofore referred to, and in that event these switches 32 and 63 may be arranged to be opened automatically upon movement of the respective control means 95 or 125 to the "full off" position previously described.

As shown in Figures 15 through 18, this may be accomplished by providing in conjunction with each switch 81 or 111, an electrically-conducting contact post 141 carrying a contact 142 and comprising an integral lateral extension 143 by which the post is riveted or otherwise suitably mounted to the base 85 or 115, a further electrically-conducting resilient arm 144 carrying a cooperating contact 145 and comprising an integral lateral extension 146 by which the arm 144 may be riveted or otherwise suitably mounted to the base 85 or 115, and on the shaft of each control means 95 or 125, a further cam 147 provided with a single projection 148 registered to engage the arm 144 and separate the contacts 142 and 145 when the respective control means 95 or 125 is in the "full off" position, as indicated in Figure 16, but to permit the contacts 142 and 145 to be in engagement both in the "full on" position, as indicated in Figure 17, and over the variable range, as indicated in Figure 18.

Obviously the above supplemental switch may be included also in the arrangements of Figures 2 and 4, also optionally the control means 95 of Figures 5 through 9 may be modified to not limit to substantially less than 100% the maximum proportion of the cycle during which the contacts 92 or 122 are closed, the control means 125 of Figures 10 through 14 may be modified to limit to substantially less than 100% the maximum proportion of the cycle during which the contacts 92 or 122 are closed, and either the control means 95 or the control means 125 may be modified to

limit to substantially more than zero the minimum proportion of the cycle during which the contacts 92 or 122 are closed, also in respect of any such limitation the maximum or minimum may be provided at whatever percentage may be preferred.

Further it will be apparent that various other changes and modifications may be made, within the purview of my invention, and accordingly it will and is to be understood that the foregoing disclosure is illustrative only, and that my invention is not limited thereto.

Wherefore I claim:

1. Switch mechanism for controlling an electric heating unit, comprising a plurality of switch contact members in the circuit to said unit and arranged to complete or disrupt said circuit, at least two of said contact members being mounted for individual and relative movement, biased to switch open position, and movable to switch closed position, and a fixed contact member positioned for coaction with one of said movable contact members and electrically connected to the other movable contact member, and actuating means operable to cyclically move said movable contact members into circuit completing contact and permit separation movement of said movable contact members into circuit disrupting position, and a variable positioning device coacting with the movable contact members to vary the actuating effect of the actuating means on said contact members whereby to vary the proportionate part of each actuating cycle during which said contact means are in and out of circuit completing engagement, said variable positioning device being further effective to completely remove the normally spaced movable contact members from the actuating influence of the cyclic actuating means and maintain said movable contact members in circuit open position, and said variable positioning device being still further effective to completely remove the normally spaced movable contact members from the actuating influence of the cyclic actuating means and to move the movable contact member other than that contact member connected to the fixed contact member into circuit completing contact with said fixed contact member.
2. Switch mechanism for controlling an electric heating unit, comprising a plurality of switch contact members in the circuit to said unit and arranged to complete or disrupt said circuit, at least two of said contact members being mounted for individual and relative movement, biased to switch open position, and movable to switch closed position, and a fixed contact member positioned for coaction with one of said movable contact members and electrically connected to the other movable contact member, and actuating means including a cam operable to cyclically move said movable contact and permit separation movement of said movable contact members into circuit disrupting position, and a variable positioning device coacting with the movable contact members to vary the spacing between said contact members relative to the effective surface of the actuating cam whereby to vary the proportionate part of each actuating cycle during which said contact means are in and out of circuit completing engagement, said variable positioning device being further effective to completely remove the normally spaced movable contact members from

the actuating influence of the cyclic actuating means and maintain said movable contact members in circuit open position, and said variable positioning device being still further effective to completely remove the normally spaced movable contact members from the actuating influence of the cyclic actuating means and to move the movable contact member other than that contact member connected to the fixed contact member into circuit completing contact with said fixed contact member.

3. Switch mechanism for controlling an electric heating unit, comprising a plurality of switch contact members in the circuit to said unit and arranged to complete or disrupt said circuit, at least two of said contact members being mounted for individual and relative movement, biased to switch open position, and movable to switch closed position, and a fixed contact member positioned for coaction with one of said movable contact members and electrically connected to the other movable contact member, and actuating means operable to cyclically move said movable contact members into circuit completing contact and permit separation movement of said movable contact members into circuit disrupting position, and a variable positioning device including movable cam surfaces coacting with the movable contact members to vary the effect of the actuating means on said contact members whereby to vary the proportionate part of each actuating cycle during which said contact means are in and out of circuit completing engagement, said variable positioning device being further effective to completely remove the normally spaced movable contact members from the actuating influence of the cyclic actuating means and maintain said movable contact members in circuit open position, and said variable positioning device being still further effective to completely remove the normally spaced movable contact members from the actuating influence of the cyclic actuating means and to move the movable contact member other than that contact member connected to the fixed contact member into circuit completing contact with said fixed contact member.

4. Switch mechanism for controlling an electric heating unit, comprising a plurality of switch contact members in the circuit to said unit and arranged to complete or disrupt said circuit, at least two of said contact members

being mounted for individual and relative movement, biased to switch open position, and movable to switch closed position, and a fixed contact member positioned for coaction with one of said movable contact members and electrically connected to the other movable contact member, and actuating means including a cam operable to cyclically move said movable contact members into circuit completing contact and permit separation movement of said movable contact members into circuit disrupting position, and a variable positioning device including movable cam surfaces coacting with the movable contact members to vary the spacing between said contact members relative to the effective surface of the actuating cam whereby to vary the proportionate part of each actuating cycle during which said contact means are in and out of circuit completing engagement, said variable positioning device being further effective to completely remove the normally spaced movable contact members from the actuating influence of the cyclic actuating means and maintain said movable contact members in circuit open position, and said variable positioning device being still further effective to completely remove the normally spaced movable contact members from the actuating influence of the cyclic actuating means and to move the movable contact member other than that contact member connected to the fixed contact member into circuit completing contact with said fixed contact member.

HADLEY F. FREEMAN.
